LOCK

Karl A. Brauning, Stamford, Conn., assignor to
The Yale & Towne Manufacturing Company,
Stamford, Conn.

Application April 3, 1930, Serial No. 441,227

16 Claims. (Cl. 70—47)

This invention relates to the cylinder locks, and more particularly to cylinder locks of the type having a sleeve portion for the accommodation of a key operated plug, and a driver containing 5 portion for housing the spring pressed drivers which control the rotation of the plug.

It has been customary in the manufacture of locking devices to use cylinder locks to control locking handles, knobs, or any other type of locking means. In order to insert the cylinder lock of usual construction into the particular device, it is necessary to provide a bore sufficiently large to permit the entrance of the entire cylinder, including the driver and key plug portions. A bore 10 or entrance of this type is rather large, and requires special construction of the housing portion or locking device in order to maintain the cylinder in operative position relatively to the same.

It is the object of my invention to provide a cylinder lock, wherein the driver chamber will be separable from and adjustable relatively to the plug of the cylinder, so that a bore or entrance considerably less than the size now required will be sufficient for the movement of the cylinder 15 into assembled position.

For a detailed description of my invention, I refer to the drawing, wherein Fig. 1 is a view of a knob containing my cylinder lock. Fig. 2 is a section on the line 2—2 of Fig. 1. Figs. 3a, 3b and 3c are sections along line 3—3 of Fig. 4 and show three views of the cylinder and the driver chamber illustrating the movement of the driver chamber relatively to the cylinder. Fig. 4 is a 20 partial section showing the relation of the driver chamber relatively to the cylinder and housing. Fig. 5 is a partially sectioned view of the driver chamber.

Referring now more particularly to the drawing, reference numeral 10 refers to a usual type of knob adapted to contain a locking cylinder casing 11 equipped with a usual type of plug 12. This cylinder casing 11 has a driver containing portion 13 and a sleeve portion 14 in 25 which the plug 12 is adapted to be rotated. The cylinder lock contains the standard tumblers and drivers adapted to be operated in the usual manner by the key 15 so that the plug 12 may be free 30 to rotate and operate whatever mechanism is desired.

In the type of construction now prevalent in the art, the driver chamber 13 is integral with the sleeve portion 14, so that knobs of special construction are required. In my invention, the 35 driver chamber 13 is slidable relatively to the

sleeve portion 14 and is equipped with a flange 16 for cooperation with a slot 17 of the sleeve 14 as seen in Fig. 4. When it is desired to secure the cylinder lock within the knob, it is merely necessary to first secure the sleeve portion 14 5 relatively to the knob, which may be done by screw-threaded means 18 as shown, or by any other desirable means. The driver portion 13 is then inserted into the plug bore of the sleeve 14 as shown in the right hand drawing of Fig. 3, 10 and is moved upwardly to the position shown in the left hand figure of Fig. 3, wherein the flange 16 is adapted to rest in the slot 17. The plug 12 is then inserted and its presence maintains this plug driver portion 13 in its upward assembled 15 position of Fig. 2 in a manner which will be quite obvious.

While I have shown but one modification of my invention, and have shown its application to a door knob, it should be understood that variations and other uses of the same will readily occur to one skilled in the art. 20

I claim:

1. In a cylinder pin tumbler lock adapted for insertion into a housing, a rotatable plug, a sleeve forming that portion of the cylinder in which said plug is adapted to be rotated, a driver chamber cooperable with said sleeve to complete said cylinder lock, said driver chamber being separable 25 relatively to said sleeve and lying partially outside of the external periphery of said sleeve when in cylinder forming relation relatively thereto, said sleeve and driver chamber when assembled requiring a larger opening for insertion into a housing than required by said sleeve when disassembled from said driver chamber. 30

2. In a cylinder pin tumbler lock adapted for insertion into a housing, a rotatable plug, a sleeve forming that portion of the cylinder in which said plug is adapted to be rotated, a driver chamber cooperable with said sleeve to complete said cylinder lock, said driver chamber being slideable 40 relatively to said sleeve and lying partially outside of the external periphery of said sleeve when in cylinder forming relation relatively thereto, said sleeve and driver chamber when assembled requiring a larger opening for insertion into a housing than said sleeve alone requires. 45

3. In a cylinder pin tumbler lock adapted for insertion into a housing, a rotatable plug, a sleeve 50 forming that portion of the cylinder in which said plug is adapted to be rotated, a driver chamber cooperable with said sleeve to complete said cylinder lock, said driver chamber being separable from said sleeve, and means on said driver chamber 55

- ber cooperable with said sleeve to maintain said driver chamber in operative relation to said sleeve, said driver chamber lying partially outside of the external periphery of said sleeve when in cylinder forming relation relatively thereto, said sleeve and driver chamber when assembled requiring a larger opening for insertion into a housing than required by said sleeve when disassembled from said driver chamber.
10. 4. In a cylinder pin tumbler lock adapted for insertion into a housing, a rotatable plug, a sleeve forming that portion of the cylinder in which said plug is adapted to be rotated, a driver chamber cooperable with said sleeve to complete said cylinder lock, said driver chamber being separable from said sleeve, said cylinder and plug being arranged to maintain said driver chamber in operative position relatively to said sleeve and partially outside of the external periphery thereof when said plug is mounted within said sleeve, said sleeve and driver chamber when assembled requiring a larger opening for insertion into a housing than required by said sleeve when disassembled from said driver chamber.
15. 5. In a cylinder pin tumbler lock adapted for insertion into a housing, a rotatable plug, a sleeve forming that portion of the cylinder in which said plug is adapted to be rotated, a driver chamber cooperable with said sleeve to complete said cylinder lock, said driver chamber being insertible into said sleeve, and adapted to be moved partially outside of the external periphery of said sleeve into operative position from within said sleeve, said sleeve and driver chamber when assembled requiring a larger opening for insertion into a housing than required by said sleeve when disassembled from said driver chamber.
20. 6. In a cylinder pin tumbler lock adapted for insertion into a housing, a rotatable plug, a sleeve forming that portion of the cylinder in which said plug is adapted to be rotated, a driver chamber cooperable with said sleeve to complete said cylinder lock, said driver chamber being separable from said sleeve, and means on the sleeve for permitting the depression of the driver chamber entirely within the periphery of said sleeve, said driver chamber being adapted to lie outside of the external periphery of said sleeve when in cylinder forming relation thereto, said sleeve and driver chamber when assembled requiring a larger opening for insertion into a housing than required by said sleeve when disassembled from said driver chamber.
25. 7. In a lock, a housing, a demountable cylinder lock adapted to be inserted into said housing, said demountable cylinder lock comprising a sleeve portion and a driver chamber, said sleeve portion and driver chamber when assembled requiring a larger opening for insertion into said housing than required by said sleeve alone requires, said sleeve having an opening, said driver chamber being separable from said sleeve portion and movable into operative position in the housing through the opening of said sleeve portion after said sleeve portion has been positioned within said housing, and means for maintaining said driver chamber in said operative position.
30. 8. In a lock, a housing, a demountable cylinder lock adapted to be inserted into said housing, said demountable cylinder lock comprising a sleeve portion and a separable driver containing portion, said sleeve portion and driver containing portion when assembled requiring a larger opening for insertion into said housing than said sleeve alone requires, said housing having an opening adapted
- for the insertion of said sleeve portion, said driver portion being adapted to be operatively positioned relatively to the sleeve portion after said sleeve portion has been inserted into said housing.
35. 9. In a lock, a housing, a demountable cylinder lock adapted to be inserted into said housing, said demountable cylinder lock comprising a sleeve portion and a separable driver containing portion when assembled requiring a larger opening for insertion into said housing than said sleeve alone requires, said housing having an opening adapted for the insertion of said sleeve portion only, said driver chamber being depressible entirely within said sleeve portion, so as to permit insertion of the cylinder into said housing.
40. 10. In a lock, a housing, a demountable cylinder lock adapted to be inserted into said housing, said demountable cylinder lock comprising a sleeve portion and a separable driver containing portion, said sleeve portion and driver containing chamber when assembled requiring a larger opening for insertion into said housing than said sleeve alone requires, the housing having an opening adapted for the insertion of said sleeve portion only, said driver chamber being depressible into said sleeve portion, so as to permit insertion of the cylinder into said housing, a key plug for said cylinder lock, said plug being adapted to maintain said driver containing portion in operative position relatively to said cylinder.
45. 11. In a lock, a housing adapted to contain a cylinder lock, said housing having an opening smaller than required for the entrance of said cylinder lock, said cylinder lock being constructed of relatively moving parts whereby it may be collapsed into a size considerably smaller than the size of the cylinder lock when its relatively moving parts are in final assembled relationship, and inserted into said housing through the small opening and then expanded into assembled operative locking relation to said housing.
50. 12. A cylinder lock adapted for insertion into a housing comprising a key plug and a sleeve portion for the maintenance of the key plug, a driver portion movable into and out of operative relationship to said sleeve portion, said sleeve portion and driver portion when assembled requiring a larger opening for insertion into a housing than required by said sleeve portion alone, said driver portion being independently secured to said sleeve by the insertion and presence of the key plug, and lying outside of the external periphery of said sleeve when in cylinder forming relation relatively thereto.
55. 13. In a cylinder lock adapted for insertion into a housing, a key plug, a cylindrical sleeve having a bore for the accommodation of said key plug, and a driver containing portion separable from said sleeve and movable into cooperative relation thereto to complete the cylinder lock with said driver portion extending outside of the external periphery of said sleeve, said sleeve and driver containing portion forming by their union and with the key plug, a complete cylinder lock, said cylindrical sleeve and driver containing portion when assembled in cooperative relation requiring a larger opening for insertion into a housing than is required for the insertion of the cylindrical sleeve only.
60. 14. In a cylinder lock adapted for insertion into a housing, a cylindrical sleeve having a bore, a key plug adapted to rotate in said bore, and a driver containing portion separable from said

5

15

20

25

sleeve and movable into cooperative relation thereto to complete the cylinder lock, said cylindrical sleeve and driver containing portion when assembled in cooperative relation requiring a larger opening for insertion into a housing than is required for the insertion of the cylindrical sleeve only, said driver and sleeve portions being maintained in operative association by said key plug with said driver portion lying at least partially outside of the external periphery of said sleeve.

15. In a cylinder lock adapted for insertion into a lock housing, a key plug, a cylinder sleeve, and a driver containing portion, said sleeve having an opening in its cylindrical walls through which the driver containing portion is movable, said cylinder being assembled by insertion of the driver containing portion into the cylindrical sleeve and then through the opening of the sleeve into its operative relation thereto, said sleeve and driver containing chamber when assembled requiring a larger open-

ing for insertion into a lock housing than said cylinder sleeve alone, the plug being then insertible into the cylindrical sleeve and into operative relation to the driver containing portion.

16. In a lock, a housing, a cylinder lock for said housing comprising a key plug, a cylindrical sleeve, and a driver containing chamber, said housing having an opening substantially the diameter of said sleeve to permit admission of said sleeve, but of such constricted size as to prevent the admission of the assembled cylinder, said sleeve having an opening in its cylindrical walls through which the driver containing portion is movable, said cylinder being assembled in said housing by insertion of the sleeve into said housing and the driver containing portion into the cylindrical sleeve and then through the opening of the sleeve into its operative relation thereto, the plug being then insertible into the cylindrical sleeve and into operative relation to the driver containing portion.

KARL A. BRAUNING.
